FIG. 6

FIG. 4

FIG. 5

FIG.10

FIG.9

FIG.8

FIG. 1 is a front elevational view of a gasoline dispensing pump showing our new design, the rear view being a mirror image of the front shown;

FIG. 2 is a right side elevational view of FIG. 1;

FIG. 3 is a left side elevational view of FIG. 1;

FIG. 4 is a front elevational view of a modified form of our gasoline dispensing pump shown in FIGS. 1 through 3, the rear view being a mirror image of the front view;

FIG. 5 is a right side elevational view of FIG. 4;

FIG. 6 is a left side elevational view of FIG. 4;

FIG. 7 is a top plan view of FIGS. 1 through 6;

FIG. 8 is a front elevational view of another modified form of our gasoline dispensing pump shown in FIGS. 1 through 7, the rear being a mirror image of the front shown, and the right side being essentially the same as shown in FIGS. 2 and 5 with the left side being a mirror image of the right side;

FIG. 9 is a front elevational view of a further modification of our gasoline dispensing pump shown in FIGS. 1 through 8, the rear being a mirror image of the front shown, and the right side being essentially the same as

shown in FIGS. 2 and 5 with the left side being a mirror image of the right side; and

FIG. 10 is a top plan view of FIGS. 8 and 9.

We claim:

The ornamental design for a gasoline dispensing pump, as shown and described.
